OSCAR C. KREIS, OF DETROIT, MICHIGAN, ASSIGNOR TO CONTINENTAL MOTORS CORPORATION, OF DETROIT, MICHIGAN, A CORPORATION OF VIRGINIA

INTERNAL COMBUSTION ENGINE

Application filed March 5, 1928. Serial No. 259,018.

This invention relates to internal combustion engines and refers more particularly to sleeve valve and like types of engines. In this general class of engines it is customary to provide a cylinder head or other structure spaced within the cylinder to form a pocket receiving one or more sleeve valves. In certain well known types of sleeve valve engines such as the Knight or the Burt-McCollum for example, the sleeve ports are moved into the sleeve pocket usually during the firing of the charge whereby the sleeve ports are cooled. It is known that the sleeve pocket tends to accumulate what is generally known as "sludge", being in the nature of carbon, oil, residue constituents of the intake and exhaust gases, and the like. It has heretofore been necessary to periodically remove the sludge accumulation by dismantling the cylinder head and scraping away the deposit since the accumulation interferes with the proper operation of the sleeve valves, produces overheating in the region of the sleeve pocket, and otherwise interferes with the desired efficient and smooth running qualities of the engine.

I have invented means for removing the matter which finds its way to the sleeve pocket. If such matter is removed periodically it may be disposed of without difficulty according to my invention, preferably before any great accumulation is experienced in the sleeve pocket. When permitted to accumulate this matter is acted upon by the heat of the engine and in time carbonizes and becomes heavily incrusted in the sleeve pocket. My invention provides for periodically removing the sludge by means preferably automatically responsive to operation of the engine whereby the sleeve pocket will be maintained substantially free from the objectionable deposits. I prefer to provide suction means acting periodically as aforesaid as I have found that in general a suction when applied constantly to the sleeve pocket tends to produce an undue accumulation of sludge in the pocket whereas a periodic suction does not in this respect appreciably alter the normal operating conditions of the engine.

A further feature of my invention resides in the provision of novel means for inducing

and controlling the suction for withdrawing the sludge from the sleeve pocket. Thus I have provided means for effecting the suction by an auto-extraction effect, utilizing the exhaust gases.

Referring to the accompanying drawing illustrating one embodiment of my invention,

Fig. 1 is a sectional elevation view through a typical sleeve valve engine illustrating my invention, and

Fig. 2 is a diagrammatic development of the cylinder and sleeve valve ports.

In the drawing reference character A represents the engine cylinder block having one or more cylinders 10. The cylinder is closed by a cylinder head B having a portion 11 depending within and spaced from the cylinder walls to form an annular sleeve pocket 12. This sleeve pocket receives one or more sleeve valves 13 ported and actuated according to the type of sleeve valve engine used. For illustration I have shown my invention in connection with the Burt-McCollum type of sleeve valve engine in which a single sleeve valve 13 is actuated by any suitable mechanism with a combined reciprocating and oscillating movement whereby any point on the sleeve such as the point 14 traces a closed curve path such as 14 with respect to the cylinder walls. The cylinder A has suitable intake and exhaust ports 15 and 16 respectively cooperating with the sleeve intake and exhaust ports 17 and 18, the sleeve valve being driven at half engine speed for the usual four stroke cycle engine.

The cylinder block A is provided with the exhaust chamber 19 open to the exhaust ports 16 whereby the exhaust gases are conducted from the engine working chamber 20. In order to utilize the extraction effect of the exhaust gases for producing a suction to remove the sleeve pocket sludge, I have provided a conduit 21 open to the chamber 19 and communicating at 22 with the sleeve pocket 12. I prefer to locate the opening 22 so that the sleeve valve will uncover the opening during at least a portion of the exhaust cycle and preferably toward the latter part of the exhaust. Thus in Figs. 1 and 2 the working chamber 20 is exhausting, the ports 18 and 16

registering and the intake ports being out of registration. The engine piston (not shown) is moving upwardly and the sleeve valve 13 is moving generally downwardly, having uncovered the opening 22. By reason of the passage of the exhaust gases through ports 18 and 16 a suction will be induced in the conduit 21 serving to remove the sludge from the sleeve pocket 12. As the cycle continues the sleeve exhaust ports 18 clear the cylinder exhaust ports 16 and intake occurs. The sleeve valve then moves generally upwardly to its extreme upper position 23 for compression and firing and thereafter exhaust again takes place completing the cycle. In the illustrated embodiment of my invention a suction is effected by the exhaust gases in the conduit 21 at a predetermined point in each cycle of the engine, it being readily understood that the degree of suction may be varied as by changing the location of the opening 22. Furthermore the sludge is disposed of through the usual exhaust system for the engine. If desired the suction may readily be arranged to act throughout the complete exhaust portion of the cycle.

While I have illustrated my invention in connection with the single sleeve Burt-McCollum type of engine, it will be apparent that the teachings of my invention are also adaptable to advantage in other types of sleeve valve engines, or in engines having sleeve pockets or generally similar pockets.

What I claim as my invention is:

1. In an engine of the sleeve valve type, a cylinder, sleeve valve means associated with the cylinder, a sleeve pocket structure accommodating the sleeve valve means, a conduit communicating with the sleeve pocket, and means inducing a suction in said conduit only during at least a portion of the exhaust cycle.
2. In an engine of the sleeve valve type, a cylinder, sleeve valve means associated with the cylinder, a sleeve pocket structure accommodating the sleeve valve means, and means removing sludge from said pocket only during at least a portion of the exhaust cycle.
3. In an engine of the sleeve valve type, a cylinder, a sleeve valve associated with the cylinder having a combined reciprocating and oscillating movement, a sleeve pocket structure for the upper end of the sleeve, said sleeve and cylinder having cooperating intake and exhaust ports, and a sludge conducting conduit having an opening into the sleeve pocket adapted to be uncovered by the sleeve during a downward movement thereof.
4. In an engine of the sleeve valve type, a cylinder, a sleeve valve associated with the cylinder having a combined reciprocating and oscillating movement, a sleeve pocket structure for the upper end of the sleeve, said sleeve and cylinder having cooperating intake and exhaust ports, and a sludge conducting conduit having an opening into the

sleeve pocket adapted to be uncovered by the sleeve during registration of the sleeve and cylinder exhaust ports.

5. A sleeve valve engine comprising in combination, a cylinder, a sleeve pocket structure, sleeve valve means operable in the sleeve pocket, exhaust gas outlet means, a conduit communicating with the exhaust gas outlet means, and an inlet port for said conduit opening into the sleeve pocket, and in communication therewith only during the exhaust cycle of the engine.

6. A sleeve valve engine comprising in combination, a cylinder, a sleeve pocket structure, sleeve valve means operable in the sleeve pocket, exhaust gas outlet means, a conduit communicating with the exhaust gas outlet means, and an inlet port for said conduit opening into the sleeve pocket and in communication therewith only during the latter portion of the exhaust cycle of the engine.

7. A sleeve valve engine comprising in combination, a cylinder, a sleeve pocket structure, sleeve valve means operable in the sleeve pocket, exhaust gas outlet means, a conduit communicating with the exhaust gas outlet means, and an inlet port for said conduit opening into the sleeve pocket, said conduit inlet port being controlled by the sleeve valve means.

8. In an engine, a cylinder block, a sleeve pocket structure, sleeve valve means within said sleeve pocket, an exhaust chamber within the cylinder block, and a conduit within the cylinder block intermediate the exhaust chamber and sleeve pocket adapted to exert a suction effect in the sleeve pocket.

9. In an engine of the sleeve valve type, a cylinder, sleeve valve means associated with the cylinder, a sleeve pocket structure accommodating the sleeve valve means, a conduit communicating with the sleeve pocket, and means inducing a suction in said conduit only during the last portion of the exhaust cycle.

10. In an engine of the sleeve valve type, a cylinder, sleeve valve means associated with the cylinder, a sleeve pocket structure accommodating the sleeve valve means, and means removing sludge from said pocket only during the last portion of the exhaust cycle.

11. In an engine of the sleeve valve type, a cylinder, sleeve valve means associated with the cylinder, a sleeve pocket structure, exhaust gas passage means, and means including a conduit for periodically placing the sleeve pocket in communication with the exhaust gas passage means.

12. In an engine of the sleeve valve type, a cylinder, sleeve valve means associated with the cylinder, a sleeve pocket structure, exhaust gas passage means, and means including a conduit for periodically placing the sleeve pocket in communication with the ex-

haust gas passage means during a portion only of the exhaust cycle.

13. In an engine of the sleeve valve type, a cylinder, sleeve valve means associated with the cylinder, a sleeve pocket structure, exhaust gas passage means, and means controlled by the sleeve valve means and including a conduit for periodically placing the sleeve pocket in communication with the exhaust gas passage means.

10 In witness whereof, I hereunto subscribe my name this 29th day of February, A. D. 1928.

OSCAR C. KREIS.
